UNITED STATES PATENT OFFICE

JAMES L. HATCHER, OF WINCHESTER, VIRGINIA

APPARATUS FOR RIFLING GUN BARRELS

Application filed July 25, 1927. Serial No. 208,313.

(GRANTED UNDER THE ACT OF MARCH 3, 1883, AS AMENDED APRIL 30, 1928; 370 O. G. 757)

The invention described herein may be manufactured and used by or for the Government for governmental purposes without the payment to me of any royalty thereon.

5 This invention relates to an apparatus for rifling gun barrels and the like.

The recent development of a type of iron and steel alloy generally designated as "stainless or unstainable" has resulted in proposals to employ it in gun barrels because its physical properties of high resistance to wear and erosion are admirably suited to this purpose.

This type of steel however possesses certain mechanical properties which are exhibited in its capacity for flowing and work hardening and because of this difficulties are presented in rifling a gun barrel by the customary machining operation. Since the foremost 20 end of the cutting tool produces a grinding rather than a cutting action the foregoing mechanical properties are reflected in a tendency of the metal to push ahead and bank up in front of the tool and also in a tendency 25 to form a hardened skin which will resist cutting. If this trouble is to be avoided by the exercise of every possible precaution the cutting operation would be extremely slow due to the hardness of the metal and it would be 30 necessary to frequently interrupt the work for the purpose of tempering the metal.

Accordingly it is proposed in the present invention to form the rifling by a cold work operation which will not only permit simultaneous formation of the rifling in a number 25 of barrels but will serve to raise the elastic limit of the metal. The apparatus employed in carrying out the invention is characterized by a novel arrangement designed to hold a 30 tool bar against bending as it is forced into the barrel.

A practical embodiment of the invention is illustrated in the accompanying drawing, wherein:

45 Fig. 1 is a view in side elevation of the tool holder;

Fig. 2 is an end view thereof;

50 Figs. 3 and 4 are detail views respectively in side elevation and plan of the rifling member.

Referring to the drawings by numerals of reference.

The apparatus employed in conducting the cold work operation includes a hollow support or holder 5 formed with a plurality of 55 equally spaced parallel guide-ways 6 in which the bars 7 carrying the rifling members 8 are reciprocally mounted.

The guide-ways are circular in form corresponding in diameter to the bore of the gun 60 barrel and all of them are provided with a slot 9 opening into the bore of the support and extending substantially throughout the length of the support in order to provide for movement of a ram 10 whose extremities fit 65 in the guide-ways.

The rifling members 8 are revolvably mounted on their bars and are each provided with spiral ribs 11. As these members are forced through the bore of the barrel the ribs 70 form a corresponding spiral channel in the wall of the bore, the metal displaced contributing towards the formation of the lands and the elastic limit of the metal of the barrel is accordingly raised.

75 In Fig. 1 the gun barrels to be worked are indicated at 12 and are rigidly held in place during the rifling operation by means of a support block 13.

I claim:

80 In an apparatus for rifling gun barrels, a support formed with a plurality of circular guide-ways each having an opening extending substantially throughout its length, bars mounted in the guide ways, rifling members 85 revolvably carried on one end of the bars and a ram mounted for sliding movement in the guide-ways and engageable with the other end of the bars.
